(74) Attorney, Agent, or Firm — Rickard K. DeMille;
Rebecca L. Henkel

(57) **CLAIM**

The ornamental design for a quick coupler for a three-point hitch, substantially as shown and described.

DESCRIPTION

FIG. 1 is a back perspective view of a quick coupler for a three-point hitch;

FIG. 2 is a front perspective view of the quick coupler;

FIG. 3 is a back view of the quick coupler;

FIG. 4 is a front view of the quick coupler;

FIG. 5 is a left side view of the quick coupler;

FIG. 6 is a right side view of the quick coupler;

FIG. 7 is a top view of the quick coupler; and,

FIG. 8 is a bottom view of the quick coupler.

Phantom lines, where utilized, are for illustrative purposes only and form no part of the claimed design.

1 Claim, 6 Drawing Sheets
